US0D1028119S

(12) **United States Design Patent** (10) **Patent No.:** **US D1,028,119 S**
(45) **Date of Patent:** **** May 21, 2024**

(54) **REVOLVER**

(71) Applicant: **Anqi Wang**, San Francisco, CA (US)

(72) Inventor: **Anqi Wang**, San Francisco, CA (US)

(**) Term: **15 Years**

(21) Appl. No.: **29/925,991**

(22) Filed: **Jan. 28, 2024**

(51) **LOC (14) Cl.** **21-01**

(52) **U.S. Cl.**

USPC **D21/574**; D21/572; D21/573

(58) **Field of Classification Search**

USPC D14/418; D21/572-574; D22/100, 104,
D22/108, 199

CPC F41C 3/14; F41C 3/00; F41A 15/02

(57) **CLAIM**

The ornamental design for a revolver, as shown and described.

DESCRIPTION

FIG. 1 is a perspective view of a revolver showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines depict portions of the revolver that form no part of the claimed design.

1 Claim, 8 Drawing Sheets
